CLAIM

The ornamental design for a window frame for access doors on a coating and drying machine as shown and described.

DESCRIPTION

FIG. 1 is a Top Perspective view of Embodiment 1 of a window frame for access doors on a coating and drying machine.

FIG. 2 is a Bottom Perspective view thereof.

FIG. 3 is a Front view thereof.

FIG. 4 is a Back view thereof.

FIG. 5 is a Left view thereof.

FIG. 6 is a Right view thereof.

FIG. 7 is a Top view thereof.

FIG. 8 is a Bottom view thereof; and,

FIG. 9 is a Top Perspective Environmental View thereof showing an environment in broken lines.

The features shown in broken lines depict environmental subject matter only and form no part of the claimed design.

1 Claim, 7 Drawing Sheets
